ABSTRACT

A support member of pliable material supports hair wound around it. A ribbon type member extends from the support member for wrapping around hair wound around the support member thereby holding the hair in position on the support member.

1 Claim, 4 Drawing Figures

HAIR CURLER

DESCRIPTION OF THE INVENTION

The present invention relates to a hair curler.

Objects of the invention are to provide a hair curler of simple structure, which is inexpensive in manufacture, used with facility and convenience, and functions efficiently, effectively and reliably to curl hair as desired with a minimum of discomfort, since it does not involve rigid, unyielding components on which the user must rest her or his head.

In order that the invention may be readily carried into effect, it will now be described with reference to 15 the accompanying drawing, wherein:

FIG. 1 is a perspective view of an embodiment of the hair curler of the invention;

FIG. 2 is a perspective view of the embodiment of 20 FIG. 1 with the hair of the user wound around it;

FIG. 3 is a perspective view of the embodiment of FIG. 1 with the ribbon type member wound around the hair which is wound around the support member thereof; and

FIG. 4 is a partly cutaway, partly sectional view of an 25 embodiment of the support member of the hair curler of the invention.

65

The support member 1 is of substantially elongated cylindrical configuration having a pair of spaced opposite ends 3 and 4 (FIGS. 1, 2 and 4).

The hair curler further comprises a ribbon type member 5 (FIGS. 1 to 3) extending from the end 3 of the support member 1. The ribbon type member 5 is wrapped around hair wound around the support member 1 thereby holding the hair in position on said support member.

While the invention has been described by means of a specific example and in a specific embodiment, we do not wish to be limited thereto, for obvious modifications will occur to those skilled in the art without departing from the spirit and scope of the invention.

We claim:

1. A hair curler, comprising
a support member of substantially pliable material
for supporting hair wound around it, said support
member being of substantially elongated unitary
cylindrical configuration having a substantially
smooth cylindrical surface and a pair of spaced
opposite ends; and
a ribbon type member extending from one of the
ends of the support member for wrapping around
hair wound around said support member thereby
holding the hair in position on said support member.
